Inventor:

Eugene J. Feighery,
by John Elias Jones,
attorney.

UNITED STATES PATENT OFFICE.

EUGENE J. FEIGHERY, OF COVINGTON, KENTUCKY.

CURTAIN-FASTENER DEVICE FOR VEHICLE-TOPS.

Specification of Letters Patent. Patented May 27, 1919.

1,305,082.

Application filed October 4, 1917. Serial No. 194,742.

To all whom it may concern:

Be it known that I, EUGENE J. FEIGHERY, a citizen of the United States of America, and a resident of Covington, in the county of Kenton and State of Kentucky, have invented certain new and useful Improvements in Curtain-Fastener Devices for Vehicle-Tops, of which the following is a specification.

10 This invention relates to improvements in curtain-fastener devices for use in connection with vehicle tops.

The invention consists of certain features of structure that are adapted to lighten, strengthen, cheapen and otherwise facilitate the manufacture and use of the class of devices herein named and described in detail in connection with the accompanying sheet of drawings, in which,—

20 Figure 1 is a plan view showing the inner face of the backing-disk in its first stage of formation from the desired blank; Fig. 2, a central cross-section of Fig. 1; Fig. 3, a view similar to Fig. 2, but showing the flange that encircles the central orifice of said disk and is spread outwardly and clenched flatly on the inner face of the backing-disk; Fig. 4, a perspective view of the nut-member in its first stage of formation but provided with 30 its required internal screw-thread; Fig. 5, an axial cross-section of the nut-member seen in Fig. 4; Fig. 6, a cross-section of the assembled backing-disk and nut-member shown in Figs. 3 and 5; Fig. 7, a cross-section of the cap-member of the fastener device taken in its first stage of formation from its desired blank; Fig. 8, a cross-section of the complete fastener device, fully assembling the several members seen in Figs. 6 and 35 7; Fig. 9, a plan of the back of the complete fastener device; Fig. 10, an elevation of said 40 complete fastener device, but showing the curtain-fastening attachment forming part of my invention herein named; Fig. 11, a cross-section of the prop-nut and curtain-fastening devices shown in Fig. 10 and showing my complete invention herein named; Fig. 12, a mixed view of four details 45 of the curtain-fastener member herein named showing them before assembling, three of the parts being in elevation and the remaining one (a washer) in perspective; and Fig. 13, a plan view of the outer face of 50 the complete device shown in Fig. 10.

55 It will be readily understood that my invention is adapted for use in connection with

the drop tops of such vehicles as buggies, carriages and automobiles.

1 indicates the back plate or disk having, initially, in the process of manufacture, a 60 central orifice 2, an inwardly-disposed flange 3 along the edge of the latter, and a peripheral flange or rim 4, as best shown in Fig. 2.

5 indicates the nut-member proper of the prop device, to which nut-member my curtain-fastener is applied. Said nut-member 65 is internally screw-threaded, and provided in its blank-form with a cylindrical extension 6 of lesser diameter than that of its body portion, as best shown in Fig. 5, and 70 such extension is not screw-threaded, for the reason hereinafter plainly disclosed.

7 indicates the external cap-member of the curtain-fastener device, whose rim 8 is clenched or spun over the flanged periphery 75 or rim 4 of the back-plate when the front and rear members are assembled.

The back-plate 1 and nut-member 5 are assembled together by inserting the cylindrical extension 6 of the nut into the central 80 orifice 2 of the back-plate 1, the flange 3 of the latter, however, having been first clenched or laid flatly in place against the inner face of the back-plate, as best shown at 3^a in Fig. 3, and then the extension 6 is 85 clenched or laid into contact with the said previously clenched flange 3, as best shown in Figs. 6, 8 and 11, making a firm and absolutely tight joint that is not subject to looseness nor rattle at any time.

90 In the curtain-fastener portion of my device, which is subject to such attachment in connection with the cap-member 7, a central orifice is provided in the latter, and a shell 9 having a flange or pair of feet 10 is inserted therein, the flange or feet 10 contacting with the underside of the cap and the body-portion of the shell extending outwardly beyond the face of the cap, as best shown in Figs. 10 and 11.

An outwardly-extending loop or open locking-handle 11 is provided in the shell 9, having its inner ends 12 clenched in flat engagement with a washer 13 that encircles said inner ends of the lock-handle, and a spiral spring 14 lies within the shell, surrounding the shank of the lock-handle 11 and expanding between the said washer 13 and the top of the shell, whereby the lock-handle is sustained in set position in notches 110 or cross-seats 15 made in the top of the shell, said cross-seats 15 being best shown in Figs.

10, 12 and 13, and, also, used in holding the said lock-handle in either open or closed position in connection with the eyelet in the curtain to be detachably-fastened in place 5 on the vehicle top.

The loop in the lock-handle is adapted for the ready insertion and use of a nail or like handy lever in case the lock-handle becomes stuck by rust, ice, or otherwise rendered difficult to turn. Besides, this form of loop lock-handle can be cheaply and easily made.

The center of the back-plate is stiffened by the flange 3 and thereby needs no other separate additional reinforce.

15 The peripheral edge of the device is both stiffened and thickened by the presence of the flange 4 and a neat, rounded surface is thus provided, similar to that of a door-knob

or the like, that would otherwise be too thin and unsightly.

20

I claim:—

A vehicle-curtain fastener comprising an outer facing-cap, an inner backing-disk having a central orifice, an inwardly-disposed and flatly-clenched flange provided in 25 the said central orifice, a threaded nut having a plain cylindrical extension of lesser diameter than that of itself and adapted to engage the said central orifice of the backing-disk for clenching-engagement in contact with the said clenched flange of the backing-disk, and means extended from the facing-cap for detachably-engaging the eyelet of a vehicle-curtain.

EUGENE J. FEIGHERY.
